UNITED STATES PATENT OFFICE.

FRANCIS H. BROWN, OF PHILADELPHIA, PENNSYLVANIA, ASSIGNOR TO COMBUSTION ENGINEERING COMPANY, A CORPORATION OF DELAWARE.

AUTOMATIC GOVERNING MECHANISM FOR CONSTANT FLUID-PRESSURE.

No. 895,239.

Specification of Letters Patent.

Patented Aug. 4, 1908.

Application filed May 17, 1907. Serial No. 374,247.

To all whom it may concern:

Be it known that I, FRANCIS H. BROWN, a citizen of the United States, residing in the city and county of Philadelphia, State of Pennsylvania, have invented a new and useful Automatic Governing Mechanism for Constant Fluid-Pressure, of which the following is a specification.

In a co-pending application, filed April 25, 1907, Serial No. 370,160, I have described and broadly claimed a novel and useful construction of a combustion and damper regulator which is adapted to be employed in connection with any desired type of furnace in order that the passage of the products of combustion from the furnace may be automatically controlled under all conditions, so that the combustion of fuel in the furnace is properly regulated and the combustion is effected under substantially uniform conditions.

In my present invention which may be used to advantage in conjunction with a construction such as is disclosed in the above mentioned application, I have devised a novel and useful construction of controlling mechanism whereby the draft of the furnace is automatically controlled by novel mechanism actuated by the variations in the steam pressure of the boiler.

To the above ends, my invention in its broad aspects comprises novel means controlled by fluid pressure for automatically actuating a governing mechanism.

It further consists of means such as a blower driven at a constant speed for producing a constant pressure in a conduit, said conduit having a branch leading therefrom and communicating with one or more furnaces below the grate, another conduit or by-pass being also provided which discharges into the atmosphere or leads to a desired point of utilization, each of said conduits branching from the main conduit being provided with a damper, both of which are actuated by a motor controlled by mechanism regulated by the variation in the steam pressure in the boiler.

It further consists of other novel features of construction, all as will be hereinafter fully set forth.

For the purpose of illustrating my invention, I have shown in the accompanying drawings, one form thereof since this embodiment will give in practice satisfactory and reliable results, although it is to be un-

derstood that the instrumentalities of which my invention consists can be variously arranged and organized and that my invention is not limited to the precise arrangement and organization of these instrumentalities as herein set forth.

Figure 1 represents a side elevation, partly broken away, of a furnace having an automatic controlling mechanism embodying my invention connected therewith. Fig. 2 represents a sectional view of another embodiment of a valve or damper which may be employed if desired. Fig. 3 represents on an enlarged scale, a portion of Fig. 1 showing the levers employed for actuating the valves or dampers.

Similar numerals of reference indicate corresponding parts in the figures.

Referring to the drawings:—Since my present invention may, if desired, be employed in conjunction with a construction such as is disclosed in my above mentioned application, I have preferred to show the same as being connected therewith.

1 designates a furnace of any suitable or conventional type, provided with a grate 2 and having a discharge pipe or outlet 3 leading from the combustion chamber 4. The passage of the products of combustion from the chamber 4 into the outlet 3 is controlled by means of a damper 5 pivoted therein, to which is secured an arm 6 provided with a suitable counter-balance 7 and having a cord 8, one end of which is secured to the arm 6, the other end thereof being secured to a suitable piston or other motor 9, as will be readily understood from my prior application to which I have hereinbefore referred.

10 designates the valve mechanism which controls the passage of fluid to actuate the motor 9, said valve mechanism 10 being operatively connected with the pivoted blade 11 mounted in the box-like casing 12 which is open at the top in order that said pivoted member 11 may be acted upon in one direction by a constant pressure such as atmospheric air, the opposite side of said member being exposed to the pressure of the furnace gases which enter through the conduit 13 into the casing member 12.

14 designates the boiler having a conduit 15 leading therefrom and communicating with a casing 16 in which is mounted a diaphragm 17, to which latter is secured a stem 18, the upper end of which extends through

the top of the casing 16 and is operatively connected with or engages a lever 19, one end of which is pivoted or fulcrumed at 20 to a suitable fixed point.

5 21 designates a valve, the stem of which is connected to the lever 19 and is adapted to control an inlet port 22 and an outlet port 23 of a valve casing which has a conduit 24 leading therefrom and opening into the piston casing 25 in which is mounted a piston 26.

10 27 designates adjustable and removable weights mounted on the stem of the piston 26.

15 28 designates a cord or cable secured to the stem of the piston 26 which passes over pulleys 29 and 30 supported in any suitable manner, the end of said cable being secured to a rod 31 upon which are adjustably secured weights 32.

23 33 designates a blower mechanism or equivalent device of any suitable or conventional type which, in the present instance, comprises a fan mounted on a shaft 34 to which latter is secured a pulley 35, around which passes a driving belt 36, which latter also 25 passes around a pulley 37 mounted on a driving shaft 38 driven by any suitable means.

39 39 designates a conduit leading from the blowing mechanism 33, said conduit in the present instance being divided into two 30 branches 40 and 41, the branch 40 communicating with the interior of the furnace below the grate 2, and the conduit 41 terminating at any desired point.

35 The conduit 41 may lead to any desired point of utilization or may be discharged freely into the atmosphere as desired.

42 42 designates a damper pivotally mounted at 43 in the conduit 40.

44 44 designates a link, one end of which is 40 fixed to the damper 42, the other end thereof having pivoted thereto, one end of a link 45, the other end thereof being pivoted to one end of a lever 46 which is pivoted at 47 to any suitable fixed point.

45 48 designates a link, one end of which is pivoted to the end of the lever 46, the other end thereof being pivoted at 49 to the rod or connection 31.

50 50 designates a damper pivoted at 51 in 52 the conduit or by-pass 41.

52 52 designates a link, one end of which is fixed to the damper 50, the other end thereof being pivoted to one end of the lever 53, which is pivoted at 54 to a suitable fixed 55 point, the other end of said lever 53 being pivoted to one end of a link 55, the opposite end of said link 55 being pivoted at 49 to the connection 31.

59 In the embodiment seen in Fig. 2, I have 60 shown a modified and simplified form of conduit controlling mechanism which comprises in the present instance a damper 56 pivoted to a rod 57 and adapted to control the conduit 40, said rod 57 having also pivoted 65 thereto, a damper 58, it being of course un-

derstood that in practice, the dampers 56 and 58 may be made integral if so desired.

The dampers have secured thereto, an arm 59 to which the connection or conduit 31 can be secured.

70 The operation of my device will now be readily apparent: As the pressure of steam in the boiler 14 increases, owing to the provision of the conduit 15, the diaphragm 17 in the casing 16 will be raised, thereby raising 75 the lever arm 19 and causing the valve 21 to close the inlet 22, thus permitting the motive fluid within the casing 25 to pass therefrom through the outlet 23. This will permit the piston 26 to descend, thereby raising the 80 links 48 and 55 and owing to the manner in which these links are operatively connected with the dampers 42 and 50, respectively, the damper 42 will be partially or wholly closed and the damper 50 will be partially or 85 wholly opened depending upon the amount of variation in the steam pressure.

90 Since the blowing mechanism 33 is always driven at a constant speed, a constant pressure of air is produced, and since the damper 42 has now been partially closed instead of the normal proportion of air passing through the conduit 40 to the furnace, a smaller quantity will pass thereto, the excess of air passing through the conduit 41 which leads to 95 any desired point.

It is apparent that the discharge of the products of combustion from the furnace is 100 regulated by the pressure of the furnace gases, since the damper 5 will be opened or closed owing to the manner in which the motor 9 is controlled by the valve mechanism 10, which latter is actuated by the swinging member 11 acted upon in one direction by constant pressure and in the opposite direction by the pressure of the furnace gases which pass thereto through the conduit 13.

105 It will also be apparent to those skilled in this art that the dampers 56 and 58 will be alternately opened and closed depending 110 upon the pressure of steam in the boiler 14, since when the cord or cable 31 is drawn upward, the damper 56 will close the conduit 40, and the damper 58 will permit the excess of pressure to pass through the branch or 115 conduit 41, which may discharge at any desired point of utilization or to the atmosphere.

120 In the devices heretofore employed in controlling the draft of the furnace, it has been deemed necessary to employ complicated mechanism for controlling the blowing mechanism and in so far as I am aware, I am the first in the art to employ a mechanism in which a constant volume or pressure is produced and automatic means controlled by variation in the steam pressure employed to divert a portion of this air into a branch leading from the main conduit, both the branch and the conduit leading to the furnace being 125 130

automatically controlled by suitable valve or other mechanism and my claims to these features are to be interpreted with corresponding scope.

- 5 In my present invention, I have shown my novel construction of regulating mechanism as adapted to automatically control the passage of air through a plurality of conduits, but it will be apparent that it may be employed to control the passage of any desired fluid such as water, oil or gas and furthermore that it is controlled by variations of pressure of any desired fluid and is not limited to use in conjunction with a steam boiler.
- 10 The device may also be employed to control the speed of an engine for driving a blower or other mechanism, or for maintaining a constant water level in the boiler.
- 15 The device may also be employed to control the speed of an engine for driving a blower or other mechanism, or for maintaining a constant water level in the boiler.

It will be further apparent that while I have preferred in the present case to show a damper as employed in a conduit, any desired or conventional type of valve may be employed.

It will now be apparent from the foregoing that I have devised a novel and useful construction of an automatic regulating mechanism which embodies the features of advantage enumerated as desirable in the statement of invention and the above description and while I have, in the present instance, shown and described one embodiment thereof, of which will give in practice satisfactory and reliable results, it is to be understood that it is susceptible of modification in various particulars without departing from the spirit and scope of the invention or sacrificing any of its advantages.

Having thus described my invention, what I claim as new and desire to secure by Letters Patent, is:—

1. In a regulating mechanism, the combination with a boiler, of means for producing a constant draft, and devices regulated by the variation in steam pressure for automatically causing a desired quantity of air to pass to the furnace and the excess to a desired point of utilization.

2. In a regulating mechanism, the combination with a boiler, of means for producing a draft of constant pressure, a conduit leading therefrom to the furnace, a branch from said conduit, dampers in said conduit and branch, and means controlled by the variation of steam pressure in said boiler for simultaneously opening one and closing the other of said dampers.

3. In a regulating mechanism, the combination with a boiler, of means for producing a draft of constant pressure, a conduit leading therefrom to the furnace, a branch from said conduit, valves for controlling said conduit and branch, and means controlled by the variation of steam pressure in said boiler for simultaneously opening one and closing the other of said valves.

4. In a draft regulator, the combination with a furnace and its boiler, of a draft producing device, means for actuating said device at a constant speed, a conduit having a plurality of branches leading from said device, one of said branches communicating with the furnace beneath its grate, dampers operatively connected with each other and controlling said branches, a motor controlling said dampers and valve mechanism controlling said motor and means actuated by the variations in steam pressure for automatically controlling said valve mechanism.

5. In a furnace, the combination with its boiler, of draft producing mechanism, driving means for actuating the latter at a constant speed, a conduit from said mechanism communicating with the furnace beneath its grate, a branch from said conduit, a motor controlled by variations in steam pressure in said boiler, and valves in said conduit and branch controlled by said motor, one of said valves being adapted to simultaneously open as the other of said valves closes.
